UNITED STATES PATENT OFFICE.

JOHN ELLIOTT MORRIS, OF COLUMBUS, OHIO.

DOOR-FASTENING MEANS.

Application filed June 2, 1926. Serial No. 113,291.

This invention relates to improvements in door fastening means, and has for its primary object the provision of fastening means of novel and improved form adapted especially for use in connection with large movable doors of the type commonly found in connection with garages or the like and wherein the fastening means is of simple and novel form capable of being positively set at a position so as to hold an associated door in a securely locked position and yet with corresponding facility to permit of the unlocking thereof.

In accordance with the invention my improved fastening mechanism consists of an elongated rod mounted for rotation about a longitudinal and vertical axis in connection with fixed bearings carried by the inner wall of an associated door, the lower end of the rod being provided with a handle to effect its axial rotation, and the upper end of the rod being provided with a fixed eccentric member, and arranged for cooperation with a keeper member fixed to and carried in connection with the door frame, the arrangement of the parts being such that when the eccentric is forced into frictional engagement with the keeper member the door will be retained in its closed or fastened position, and when the rod is rotated to remove the eccentric from frictional engagement with the keeper member, the rod together with its eccentric is allowed to drop or fall to a position out of registration with the plane of the keeper member, thus allowing the door to be swung or otherwise moved to an open position without interference on the part of the fastening mechanism.

With these and other objects in view, as will appear as the description proceeds, the invention consists in the novel features of construction, combinations of elements and arrangements of parts hereinafter to be fully described and pointed out in the appended claim.

In the accompanying drawing:

Figure 1 is a perspective view disclosing the improved door fastening mechanism comprising the present invention,

Figure 2 is a vertical longitudinal sectional view,

Figure 3 is a horizontal cross-sectional view on the line 3-3 of Figure 2,

Figure 4 is a detail sectional view showing the lock in connection with a floor member.

Referring more particularly to the drawings the numeral 1 designates a door of suitable form, purpose or type. For present purposes it may be said that the door 1 is used in connection with the door-way of a garage or other similar building and is suitably mounted, for example, in connection with hinges, so as to be capable of being moved to assume the positions either opening or closing the door-way. The door is mounted in connection with a suitable type of door frame 2, which latter in this instance is recessed as at 3 to receive the edge of the door and provide a stop to limit its inward or closing movement.

Mounted upon the inner wall of the door are bearing brackets 4, preferably formed from castings so as to provide base portions 5 which are secured in a rigid manner to the inner wall of the door. The outer portions of the horizontally and laterally extending brackets 4 are provided with bores 6, which are adapted to rotatably receive a vertically extending shaft or rod section 7, in order that said section may be retained in connection with the door for both sliding and rotatable movement.

In this instance the upper end of the shaft or rod section 7 is formed or provided with a fixed eccentric 8, arranged for rotation about the vertical axis of the shaft section and in a substantially horizontal plane. This eccentric is adapted for cooperation with a fixed keeper member 9 which, preferably, is formed from a metallic casting and includes a horizontal base wall 10 suitably secured as at 11 in connection with the upper portion of the door frame 2. Further, the keeper member is provided with a chamber 12, having an open rear side and a short, lower horizontally disposed wall 13, constituting a locking shoulder.

In operation, it will be seen that by rotating the shaft or rod section 7, and this may be conveniently accomplished by providing the lower end of said section with an out-turned horizontally disposed handle 14, rotary movement will be imparted to the eccentric 8. This results in bringing that portion of the eccentric which possesses the smallest radii with respect to the axis of the shaft section in registration with the wall 13 of the keeper member. Inasmuch as the eccentric is proportioned so that when the shorter radii thereof is presented to the keeper member there will be no frictional

contact of the eccentric with said keeper member, and the rod section will be permitted to drop, so that the eccentric proper will rest upon the upper surface of the upper bearing bracket 4, in a plane below and independent of the fixed keeper member 9. Obviously, this permits the associated door to be opened and closed at will without interference of any kind from the fastening mechanism. To fasten the door the reverse procedure is followed, wherein the shaft section 7 is elevated to bring the eccentric into registration with or in the plane of the keeper member. Then by rotating the shaft section that portion of the eccentric possessing the largest radii is moved into the chamber 12 above the wall 13 and frictionally sustained and held in engagement with said keeper member so as to positively fasten the door in connection with the jamb or frame 2. It is of course within the scope of the invention to substantially reverse this construction and lock the door in connection with the floor or lower part of the door jamb 25 rather than in connection with the upper part thereof.

This fastener is not only extremely simple and cheap in construction, but may be readily operated and performs its several functions in a positive manner without structural complication such as is apt to be present when springs and other multiplied parts are employed.

It will be observed upon reference to Figure 3 that when the eccentric occupies its locked position the same is swung past the center line indicated by the line $a-a$, so that the handle 14 will engage the inner surface of the door. This position is permitted due to the fact that the upper end of the rod 7 may spring a trifle so as to produce a resilient action or spring pressure on the eccentric. This results in positively maintaining the eccentric in its locked position, preventing undue rotation thereof after manual release. To release the door positive pressure is required to rotate the eccentric so as to bring the same past the

center line $a-a$. The eccentric is preferably provided with a socket in which the 50 tapering and squared upper end of the rod or shaft 7 is positioned. The cotter pin or the like may be employed for retaining the eccentric on the end of the shaft. This construction permits of the reversal of the position of the eccentric so as to adapt the same to operating positions either on the top or bottom of the door. In Figure 4 the device has been shown as mounted on the bottom 60 of a door, wherein the eccentric is positionable within a casing 17 embedded in the floor 18 adjacent to the lower edge of the door 1. In this instance the spring 19 surrounds the shaft 7 and normally maintains the eccentric out of the casing 17. However, by pushing downwardly on the rod 7 the eccentric may be positioned as shown in Figure 4, whereby upon rotation of the shaft the frictional engagement between the walls of the casing and the eccentric will hold the 70 latter in its locking position even against the elevating influence of the spring 19. Of course, a shoulder or lip may be used in this form of the construction if desired.

What is claimed is: 75
The combination with a fixed frame and a relatively movable closure member, of a vertically disposed shaft section rotatably and slidably journaled in connection with bearings carried by the inner wall of said closure member, an eccentric provided upon the upper end of said shaft section, a keeper member carried by the fixed frame and formed with a chamber for the reception of said eccentric so as to frictionally engage 80 that portion of said eccentric possessing the greatest radii with respect to the longitudinal axis of said shaft section, and a wall formed with said chamber and arranged to underlie a portion of said eccentric when 85 the latter occupies said chamber and to clear said eccentric when the said eccentric is out of engagement with said keeper.

In testimony whereof I affix my signature.

JOHN ELLIOTT MORRIS.
